UNITED STATES PATENT OFFICE.

EDWARD B. VAUGHAN, OF SELMA, ALABAMA.

COTTON-PICKER.

SPECIFICATION forming part of Letters Patent No. 752,272, dated February 16, 1904.

Application filed September 23, 1903. Serial No. 174,364. (No model.)

To all whom it may concern:

Be it known that I, EDWARD B. VAUGHAN, a citizen of the United States, residing at Selma, in the county of Dallas and State of Alabama, have invented certain new and useful Improvements in Cotton-Pickers, of which the following is a specification.

This invention relates to improvements in hand-operated mechanism for crop-gathering, and particularly to such as is especially designed for picking cotton.

The object in view is the provision of means for facilitating the position of a boll and means for removing the cotton therefrom after such positioning.

The invention comprises certain novel constructions, combinations, and arrangements of parts, as will be hereinafter fully described and claimed.

In the accompanying drawings, Figure 1 represents a perspective view of a cotton-picking mechanism embodying the features of the present invention. Fig. 2 represents a view in side elevation of the same. Fig. 3 represents an enlarged fragmentary perspective view of the cotton-removing fingers and surrounding parts.

Referring to the drawings by numerals, 1 indicates a suitable framework provided with an operating-handle 2, extending rearwardly therefrom and carrying at its forward end lateral projecting brackets 3, 3, engaging the tubular casings 4, 4 and supporting the same in position at an acute angle to each other, 35 and tapering to the apex, where the said casings are secured together by a bracket 5, formed with a suitable journal 6, carrying a pulley 7, about which pulley is passed an endless belt 8, said belt passing throughout the 40 length of casings 4 and at the rear about a driving-pulley 9, said driving-pulley being provided with an operating-handle 10. The pulley 9 is journaled in the frame 1 in any suitable manner and is preferably provided 45 with annular edge flanges for guarding against lateral play of the belt 8. The pulley 9 is of a diameter equal approximately to the distance between the rear ends of casings 4, so as to receive the belt 8 without unnecessary friction 50 against the ends of said casing.

Any suitable bag or container 11 may be suspended from framework 1 in any preferred manner and is adapted to receive the cotton from the carrier-belt 8, which in operation is discharged from the same as it passes about 55 pulley 9.

The belt 8 is provided with series of teeth 12, extending from the surface thereof and designed in operation to engage the cotton, suitable fingers 13, 13 being carried by frame 1 and extending in an inclined plane in contact with the belt 8 outside the path of movement of the various teeth of the several series 12.

The bracket 5, carrying pulley 7, is provided with a boll-engaging finger or member 14, formed hook-shaped and inclined toward the plane of the belt 8 for purposes hereininafter specified.

In operation the drum 9 is driven in the direction indicated by the arrow, and the mechanism is positioned with the member 14 engaging the stem of a boll for retaining the same with the cotton in position for being engaged by the teeth 12. The cotton will thus be removed and carried along through the upper casing 4 and about the pulley 9 until engaged by fingers 13, which lift the same and drop the cotton into the receptacle 11.

Among the many advantages obtained by the present structure may be observed the fact that the member 14 may be employed for lifting an inverted boll and positioning the same without necessitating the operator stooping to pick up the boll. Further, the fact that the casings 4 are cylindrical permits any lateral turning or twisting of the belt without endangering clogging of the parts by entangling the cotton fiber with the surrounding casing. The flanges on the pulley 9 positively guide the belt 8, and thereby have a direct correlation to and coaction with the fingers 13, preventing contacting of said fingers with the teeth 12 through lateral movement of the belt.

Having thus fully described my invention, what I claim as new, and desire to secure by Letters Patent, is—

1. In a hand-operated cotton-picker, the combination with a frame, of a belt movable longitudinally thereof, cotton-picking means carried by said belt, and a fixed boll-

engaging member projecting from the end of said frame beyond said belt.

2. In a cotton-picker, the combination with a frame and cotton engaging and conveying mechanism carried thereby, of a boll-engaging hook projecting from the end of said frame.

3. In a cotton-picker, the combination with a frame, a belt carried thereby, and cotton-picking means carried by said belt, of a boll-engaging member projecting from said frame at one side of the belt and inclined toward the other.

4. In a cotton-picker, the combination with a frame, an endless belt carried thereby, and tapering approximately to a point, and cotton-picking means carried by said belt of a hook projecting beyond said point.

5. In a cotton-picker, the combination of tubular casings, means securing the same together and forming a frame, an endless belt extending through said casing, cotton-picking means carried by said belt, and means for driving the belt.

6. In a cotton-picker, the combination of

tubular casings connected at one end and flaring rearwardly therefrom, an endless belt extending through said casing, cotton-carrying means on said belt, and means for driving said belt.

7. In a cotton-picker, the combination of tubular casings connected at one end and flaring rearwardly therefrom, a bracket carried by said casings at their front end, a pulley journaled in said bracket, an endless belt extending through said casings and passed about said pulley, and means for driving said belt.

8. In a cotton-picker, the combination of casings connected at their front end, a bracket carried by said casings at their front end, cotton-conveying means extending through said casings, and a boll-engaging finger projecting from said bracket.

In testimony whereof I affix my signature in presence of two witnesses.

EDWARD B. VAUGHAN.
